UNITED STATES PATENT OFFICE.

PAUL MAUSER, OF OBERNDORF-ON-THE-NECKAR, GERMANY.

SMALL-ARM BULLET.

1,053,844.

Specification of Letters Patent.

Patented Feb. 18, 1913.

Application filed October 26, 1910. Serial No. 589,235.

To all whom it may concern.

Be it known that I, PAUL MAUSER, privy commercial councilor, a subject of the King of Wurttemberg, residing at Oberndorf-on-the-Neckar, in the Kingdom of Wurttemberg, Germany, have invented certain new and useful Improvements in Small-Arm Bullets, of which the following is a full, clear, and exact description.

10 As is known the infantry ammunition with pointed bullet heretofore employed presents two defects, one of them residing in the fact that the attachment of the bullet to the cartridge case is somewhat insecure owing to the fact that the bullet is not inserted far enough, while the second defect is that owing to defective dimensioning of the length of point or in the distribution of the weight in the core, the center of gravity of the bullet is located too far rearward, whereby "keyholes" are frequently caused.

Now the present construction has for its object to remove these defects and to provide a bullet which, while retaining the external dimensions of the cartridges heretofore employed including their length and without appreciably altering the weight of the bullet, permits of providing the necessary insertion length for obtaining secure attachment in the cartridge case and also of shifting the center of gravity to the front part of the bullet thereby to insure certain position in the trajectory.

35 In the accompanying drawing which illustrates the invention: Figure 1 shows an ordinary bullet M. 98. Figs. 2 and 3 show two bullets embodying the invention in longitudinal section inserted in their cartridge case. Fig. 4 shows a modified form of my invention.

40 As shown by this drawing the improved bullet is extended rearward beyond the front lead-filled core portion presenting approximately the length of the bullet heretofore usual in such a manner that behind the end of the effective lead core k^1 a special insertion portion is formed which is slightly conical at its rear end, its core k^2 consisting of light metal. The two cores k^1 k^2 are 45 closed by a single metallic casing m ; the contact faces of the lead and the light metal cores can either be flat (Fig. 2) arched, or

more or less conical (Fig. 3) in order that when firing takes place the rear end of the lead core may be distended thereby affording an improved guidance of the bullet in the barrel as compared with the guidance hitherto afforded.

50 The lengths and weights of the two core portions are calculated in such a manner that while preserving the normal weight of bullet of about 10 to 11 grams the center of gravity is located inside the guide portion or in front thereof.

55 Fig. 4 shows a form of bullet in which the rear light metal core k^2 is turned with a peripheral groove k^3 by means of which when the bullet enters the barrel, its passage into the rifling is facilitated that is to say the hardness or harshness of the guidance of the bullet which has heretofore existed is reduced. The diminution of the frictional area on fired bullets shows that this effect is attained. Already with this novel form of bullet the bullet velocity has been increased 75 by about 20 meters for a given charge.

What I claim as my invention and desire to secure by Letters Patent is:

1. An enveloped bullet for small arm ammunition consisting of a casing, a solid core 80 of heavy material in the front portion of said casing and a solid core of light material in the rear portion of said casing, said core of light material having a peripheral groove adapted to facilitate the penetration of the 85 bullet into the rifling.

2. An enveloped bullet for small arm ammunition consisting of a casing, a solid core of heavy material in the front portion of said casing and a solid core of light material 90 in the rear portion of said casing, said core of light material having an arched contact face with respect of the core of heavy material and a peripheral groove adapted to facilitate the penetration of the bullet 95 into the rifling.

In witness whereof, I have hereunto signed my name in the presence of two subscribing witnesses.

PAUL MAUSER.
